UNITED STATES PATENT OFFICE.

JOHN C. McLAUGHLIN, OF JERSEY CITY, NEW JERSEY, ASSIGNOR TO UNDERWOOD
TYPEWRITER COMPANY, OF NEW YORK, N. Y., A CORPORATION OF DELAWARE.

TYPE-WRITING MACHINE.

1,211,203.

Specification of Letters Patent.

Patented Jan. 2, 1917.

Application filed April 13, 1915. Serial No. 20,987.

To all whom it may concern:

Be it known that I, JOHN C. McLAUGHLIN, a citizen of the United States, residing in Jersey City, in the county of Hudson and 5 State of New Jersey, have invented certain new and useful Improvements in Type-Writing Machines, of which the following is a specification.

This invention relates to mechanism by 10 which the ribbon of a typewriting machine is vibrated to cover and uncover the printing point at each type-stroke, and is particularly adapted for use with a ribbon comprising a plurality of color bands or stripes. In 15 such machines, the ribbon vibrator is commonly operated by a universal bar lying in the path of the type bars, and actuated at each type stroke. The universal bar is usually operated only during the final portion 20 of the type-stroke, and as the type bar is moving with great rapidity as it approaches the platen, the time permitted for the ribbon vibrator to be thrown up to position over the printing point by the universal bar is extremely short, so that the vibrator must be moved with great rapidity. The 25 usual devices cannot be relied on to throw the ribbon to operative position ahead of the type bar, and at the same time prevent the ribbon from overthrowing. These difficulties are accentuated when a bichrome ribbon 30 is used, because of the fact that the color bands are narrow and do not permit of much latitude in the position of the ribbon over the printing point, and also because of the greater throw of the ribbon needed to bring the lower color band over the printing point.

An object of the present invention is to 35 overcome these difficulties by providing means to secure a comparatively high speed of the ribbon vibrator during the initial portion of its throw, so that the ribbon is positioned over the printing point, before the type is very close to the platen, the final movement of the ribbon being comparatively slow, thereby reducing the tendency to overthrow.

The invention further provides improved 40 means for positively stopping the vibrator with the ribbon over the printing point, thus positively preventing overthrow of the ribbon. Such stopping means is designed to

be effective for different case positions of the platen, and with either color band operative.

The invention further provides a compact arrangement of the ribbon vibrating mechanism in close proximity to the universal bar, and in which the operation of the universal bar on said mechanism is direct, and lost motion and yielding of parts eliminated or reduced to a minimum. Accuracy and uniformity in the operation of the ribbon vibrator are thus attained.

The invention further provides an improved form of universal bar and supporting means therefor, designed to prevent springing or distortion of the bar when struck by the outlying type bars, thus insuring a uniform action of the universal bar and ribbon vibrating mechanism for all the type bars.

In practising the invention, the ribbon vibrator or guide may be moved up and 45 down by a vibrator lever pivotally mounted on a plate or support, the latter shiftable up and down with the platen to maintain the ribbon in operative relation to the platen for both case positions. The said support 50 may also have mounted thereon an actuator in the form of a bell crank, one arm of which is connected through a link to the vibrator lever, said arm and lever forming a toggle. The other arm of the bell crank 55 is connected through a switch to the universal bar, so that when the universal bar is actuated by a type bar, the bell crank operates through said link to throw the ribbon vibrator up over the printing point.

The toggle formed by the bell crank arm and link multiplies the movement transmitted to the vibrator, and the arrangement of said arm and link is such that the parts of the toggle are moved toward a straight line 60 position during the upward throw of the vibrator. The result of this arrangement is that the speed of the vibrator relative to the bell crank actuator is comparatively high at the commencement of the throw, and is 65 gradually reduced throughout the throw. The ribbon is thus positioned over the printing point before the type is very close thereto, and the tendency to overthrow the ribbon is also reduced.

The switch may be pivoted on the univer-

sal bar and is key-actuated to shift the point of connection between the switch and bell crank toward or from the pivot of the latter to vary the throw of the ribbon, so that either color band may be brought into activity. A stop to prevent overthrow of the ribbon may be shifted by the switch whereby different stop surfaces of the stop are brought into operative positions corresponding to the operative color band. The universal bar may be supported on a hanger comprising a rock shaft having arms pivoted to the bar and providing a rigid construction preventing distortion of the bar under the stress of outlying type bars striking the universal bar adjacent its ends.

Other features and advantages will hereinafter appear.

In the accompanying drawings, which illustrate an embodiment of my invention as applied to an Underwood typewriting machine, Figure 1 is a fragmentary rear elevation view, partly in section, and indicating in broken lines the position of the platen. The ribbon vibrating mechanism is shown in the position assumed when the platen is in lower case position, the lower color band operative, and the vibrator in its lower or normal position of rest. Fig. 2 is a sectional side elevation of the machine, the parts being in the same position as in Fig. 1. Figs. 3 to 8 inclusive illustrate various positions of the ribbon vibrating mechanism, when the type bar is in printing position. Fig. 3 is a sectional side elevation showing the platen in lower case position and the upper color band operative. Fig. 4 is a fragmentary rear elevation view, the parts being in the same position as in Fig. 3. Fig. 5 shows the platen in lower case position, and the lower color band operative. Fig. 6 is a view similar to Fig. 3, but showing the relation of parts when the platen is in upper case position. Fig. 7 is a rear elevation showing the position of parts when the lower color band is operative and the platen in upper case position. Fig. 8 is a sectional side elevation with the parts in the Fig. 7 position. Fig. 9 is a rear perspective view showing the parts in their normal positions of rest, the upper color band being operative. Fig. 10 is a rear elevation view with the ribbon mechanism in non-printing position. Fig. 11 is a grammatic view.

Referring to Fig. 2, the roller platen 11 is journaled in the platen frame 12, mounted on the carriage 13 and shiftable up and down thereon to bring the platen to upper and lower case positions. A roller 14 on the platen frame runs on a shift rail 15 which may be operated by the usual shift keys for shifting the platen. The type bars 16 fulcrumed on a rod 17, are actuated by 65 keys 18 connected to the type bars through

bell cranks 19, so that the depression of a key 18 throws the connected type bar upwardly and rearwardly to cause a type 20 thereon to strike against the front face of the platen.

The carriage may be driven by the usual spring drum, (not shown), and the letter-feed movement of the carriage is controlled by escapement mechanism comprising a dog rocker 21, and an escapement wheel 22, 70 which the dogs 23 in said rocker engage, the dog rocker being actuated by a universal bar at each type-stroke. A pinion 24 connected to drive the escapement wheel 22 during the letter-feed travel of the carriage, 80 runs in mesh with a rack 25 on the carriage. The universal bar 26 lies in the path of shoulders 27 on the type bars 16, and at each type stroke, a shoulder 27, strikes the universal bar as the type bar approaches the 85 printing point and moves the universal bar rearwardly, a rearward extension 28 of the universal bar striking the dog rocker to actuate the latter. The extension 28 has a sliding connection with a standard 29 on 90 the machine frame, whereby the bar is supported and guided.

The universal bar is hung on a rocker frame comprising a rock shaft 30, which may be supported on the machine frame, 95 and has depending rock arms 32 pivotally connected at 33 with the universal bar near the ends thereof. This arrangement prevents any twisting or distortion of the universal bar when struck adjacent its end by 100 an outlying type bar. In other words, the frame 30, 32, prevents either end of the universal bar from springing or yielding without an equal movement in the same direction of the entire bar. The operation of the 105 universal bar in transmitting motion from the type bars to the escapement mechanism and ribbon vibrating mechanism is thus uniform and reliable for all the type bars.

Referring to Fig. 9, the ribbon vibrating 110 mechanism comprises a ribbon vibrator or guide 34 through which the ribbon 35 is threaded, and by which said ribbon is vibrated over the printing point at each type-stroke. The ribbon preferably comprises a 115 plurality of color bands or zones for printing in different colors, and as shown, comprises an upper black band 36, and a lower red band 37. The vibrator is actuated by a vibrator lever 38 connected by the pivot 39 120 to the vibrator and pivoted at 40 to a support 41. This support is shown as a plate mounted on the rear face of the type bar segment 31, and shiftable up and down thereon with the platen frame, as the latter 125 is shifted to upper and lower case positions, thereby maintaining the ribbon vibrator in operative relation to the platen in both case positions.

The means for shifting the support 41 130

with the platen, comprises a bracket 42 secured to the shift rail 15, and projecting forwardly therefrom, the forward end of said bracket having a slot-and-pin connection 43 with the plate 41. This slot-and-pin connection permits a limited up and down movement of the bracket 42 relative to the plate 41, to compensate for the greater vertical throw of the forward end of said bracket, 5 as compared with the throw of the shift rail 15, owing to the greater distance of said forward end of the bracket from the horizontal fulcrum about which rotates the shift frame comprising the rail 15. The parts are 10 preferably so proportioned that when the platen is shifted from lower to upper case position, the support 41 is lifted the same distance as the platen, and the relation of the ribbon and platen thereby remains 15 unchanged. 20

The ribbon vibrator lever 38 is actuated by a bell crank lever 44 connected by a pivot 45 to an arm or bracket 46 fixed to and projecting rearwardly and downwardly from 25 the plate 41. The bell crank comprises a depending arm 47 having pins 48 and 49, projecting from opposite sides thereof and adapted to engage respectively slots 50 and 51, in a switch 52, connected by a pivot 53 30 to an up-turned lug 54 of the universal bar 26. The rearwardly extending arm 55 of the bell crank is connected through a link 56 with the lever 38, the link being pivoted at 57 to the bell crank and connected by a 35 ball-and-socket joint 58 to the lever 38.

The link 56, (see Figs. 3 and 4) is bent at 59, the lower end of the link being bifurcated as shown, to straddle the arm 55 of the bell crank. It will be understood, however, that 40 this link may be straight or made in some other form if desired.

When the parts are adjusted for printing through the upper color band, (Figs. 3 and 4), with the platen in lower case position, 45 the pin 49 on the bell-crank is in engagement with the slot 51 of the switch, so that when a type bar 16 is thrown up to the platen, the rearward movement of the universal bar when struck by the type bar, carries the switch rearwardly and swings the 50 bell crank. The movement of the bell crank arm 55 imparts an upward thrust to the link 56, thereby actuating the lever 38, and moving the color band 36 over the printing 55 point.

It will be observed that the bell crank arm 55 and the link 56 together form a toggle, and that the members of the toggle are moved toward a straight line position during 60 the type-stroke. As a result of this arrangement, the vertical movement of the link 56, at its point of connection with the vibrator lever 38, relative to the angular movement of the arm 55 of the bell crank, is 65 greatest at the beginning of the upward

throw of the vibrator, and gradually decreases during said throw. In other words, the most rapid movement of the ribbon occurs during the initial rearward movement of the universal bar, so that the ribbon is 70 well advanced over the printing line before the type bar is very close to the platen. Interference between the type bar and ribbon is thus avoided and the proper positioning of the ribbon over the printing point is as- 75 sured. A further result of this arrangement is that the ribbon is gradually slowed down and the tendency to overthrow is greatly reduced. It will be noted that with the toggle connection, the speed of the bell 80 crank is multiplied at the vibrator lever 38; or, stated another way, the speed of the link at the point of connection 58 with the vibrator lever is approximately double that of the bell crank arm 55 at the pivot 57. 85

In order to bring the lower color band 37 into activity, the switch 52 is thrown to the position shown in Fig. 1, so as to withdraw the pin 49 from the slot 51, and project the pin 48 into the slot 50. The switch is 90 actuated by keys 60 and 61, fixed to a rock shaft 62 to which is also fixed a rock arm 63 connected through a link 64 to the switch. The pin 48 being nearer than the pin 49 to the fulcrum of the bell crank, a greater 95 throw is imparted to the vibrator, and the latter is brought to the position shown in Fig. 5. The slots 50 and 51 are elongated to permit the shifting of the bell crank actuator relatively to the switch. 100

Means to positively prevent overthrow of the ribbon comprises a stop device 65, shown as a rod slidably mounted in a horizontal sleeve 66, fixed to the shiftable support 41. A pin 67 on the slidable stop device extends 105 through a slot 68 in the sleeve 66, and projects rearwardly into a slot 69 in an arm 70, formed on the switch 52. A pin 71 on the ribbon vibrator forms a counter stop to engage the stop 65 and thereby limit the up- 110 ward throw of the vibrator.

When the switch is positioned (Fig. 4) for printing through the upper color band, the pin 71 engages the body of the stop 65, but when the switch is thrown to the Fig. 1 115 position, to bring the lower color band into activity, the stop device 65, by means of the slot-and-pin connection 67, 69, is moved to the left (Fig. 1) to permit the vibrator to move upwardly until the pin 71 has passed 120 beyond the body of the stop device and is arrested by an upwardly offset extension 72. It will thus be seen that the stop device provides two stops which are alternatively brought into operative position by the shift- 125 ing of the switch, and the operative positions of said stops correspond to the positions of the ribbon in which the color bands are respectively operative. As the stop 65 is mounted on the shiftable support 41, it is 130

carried up and down with the platen as the latter is shifted to upper and lower case positions and thus provides stopping means for the vibrator operative for all adjustments of the platen and ribbon mechanism.

5 When the platen is in upper case position the shifting pin 67 on the stop device is at a greater distance from the pivot of the switch than when the platen is in lower case position. The operation of the switch arm 10 70, would therefore tend to shift the stop 65 a greater distance, but this is compensated for by increasing the width of the upper portion of the slot 69, thereby introducing lost motion between the switch and stop device.

15 Fig. 10 illustrates the switch 52 at an intermediate position in which it is disconnected from the actuating lever 44, so that the ribbon is silenced; that is, it is not vibrated over the printing point when the types are actuated. The switch is locked in non-printing position by a locking lever 73, pivoted at 74, and provided with a slot to 20 receive a pin 75 on the key lever 76.

25 Variations may be resorted to within the scope of the invention, and portions of the invention may be used without others.

Having thus described my invention, I 30 claim:

35 1. The combination with a ribbon vibrator and a universal bar, of means for transmitting motion from the universal bar to the vibrator, said means comprising a bell crank having an arm to which a forward and rearward movement is imparted by the universal bar, and an arm having an up and down movement, and a link connected between said last-mentioned arm and the vibrator for 40 moving the latter up and down, said last-mentioned arm and link forming a toggle arranged to gradually decrease the speed of the vibrator relative to that of the actuator during the upward throw of the vibrator.

45 2. The combination with a platen shiftable to upper and lower case positions, of a universal bar, a ribbon vibrator, an actuating lever for said vibrator, a support on 50 which said lever is mounted, said support being shiftable up and down with the platen, a link between said lever and vibrator forming with said lever a toggle, and connections between the universal bar and said lever for 55 operating the latter and permitting the lever to shift with the platen.

60 3. In a typewriting machine, the combination with a platen shiftable to upper and lower case positions, of a ribbon vibrator, a vibrator lever connected thereto, a support on which said lever is mounted, means to shift said support up and down with the platen, an actuating lever mounted on said support, a link connecting one arm of said 65 actuating lever with the vibrator lever and

70 forming with said arm a toggle, and means to operate said actuating lever at each type stroke and cause the members of the toggle to be moved toward a straight line position during the type stroke whereby the ribbon vibrator is operated at a gradually decreasing speed.

75 4. In a typewriting machine, the combination with a platen shiftable to upper and lower case positions, of a ribbon vibrator, a vibrator lever connected thereto, a support on which said lever is mounted, means to shift said support up and down with the platen, an actuating lever mounted on said support, a link connecting one arm of said 80 actuating lever with the vibrator lever and forming with said arm a toggle, a universal bar actuated by the type-bars, and means providing a slot-and-pin connection between the universal bar and said actuating lever 85 permitting the latter to shift up and down with the platen, while maintaining an operative relation between the universal bar and actuating lever.

90 5. In a typewriting machine, the combination with a platen shiftable to upper and lower case positions, of a ribbon vibrator, a vibrator lever connected thereto, a support on which said lever is mounted, means to shift said support up and down with the 95 platen, an actuating lever mounted on said support, a link connecting one arm of said actuating lever with the vibrator lever and forming with said arm a toggle, a universal bar operated at each type stroke, and a 100 switch connected to the universal bar, and shiftable thereon to connect the universal bar with said actuating lever at different distances from the fulcrum of the lever to vary the throw of the latter and thereby 105 vary the throw of the ribbon vibrator to bring the different color bands of a bichrome ribbon carried by the vibrator into activity, the switch having a slidale connection with the actuating lever while the switch is in 110 either of its shifted positions to permit the actuating lever to shift up and down with the platen.

115 6. In a front-strike typewriting machine, the combination with a platen shiftable up and down to upper and lower case positions, 120 of a ribbon vibrator, a vibrator lever pivoted thereto, a support on which said lever is mounted, means to shift said support and vibrator lever up and down with the platen to thereby cause the ribbon to be shifted up and down with the platen, a bell crank lever pivoted on said support beneath said vibrator lever, and comprising a depending arm, a universal bar operated at each type stroke 125 and connected to said depending arm to impart a rearward movement thereto, the bell crank lever comprising a rearwardly extending arm having an up and down movement, and a link connecting said rearwardly ex- 130

tending arm with said vibrator lever, and operable to move the vibrator upwardly to cover the printing point at each type stroke.

7. In a typewriting machine, the combination with a ribbon vibrator for a bichrome ribbon, of an actuator for said vibrator, a universal bar, a switch forming an operating connection between the universal bar and said actuator for causing the latter to operate the vibrator, said switch shiftable to vary the connection between the universal bar and actuator, and thereby vary the throw of the ribbon vibrator, to bring different color zones of the ribbon into activity, a stop device to limit the throw of the vibrator, and means operated by said shifting of the switch to shift the stop device and thereby vary the stopping position of the vibrator. 70 75 80

8. In ribbon mechanism for a typewriting machine, the combination with a vibrator for a bichrome ribbon, of means to actuate said vibrator, a stop device in the path of the vibrator for limiting the throw thereof, and a switch shiftable to vary the throw of the vibrator to bring different color bands of the ribbon into activity, said stop device shiftable to different stop positions by said shifting of the switch, to thereby change the stopping position of the vibrator. 85

9. In a typewriting machine, the combination with a ribbon vibrator, of an actuator therefor, a platen shiftable to upper and lower case positions, a support on which said actuator is mounted, means to shift said support with the platen and thereby cause the vibrator to be shifted with the platen, a stop device mounted on said support and shiftable therewith, and a counter stop mounted to shift with the vibrator and platen to different case positions, said counter stop connected to vibrate with the vibrator and coöperating with said stop device to limit the throw of the vibrator. 90 95 100

10. In a typewriting machine, the combination with a ribbon vibrator, of an actuator therefor, a platen shiftable to upper and lower case positions, a support on which said actuator is mounted, means to shift said support with the platen and thereby cause the vibrator to be shifted with the platen, a stop device mounted on said support and shiftable therewith, a counter stop on the vibrator and coöperating with said stop device to limit the throw of the vibrator, means to vary the throw of the vibrator to bring different color bands of a ribbon into activity, and means to shift said stop device when the throw of the vibrator is changed, and thereby position the stop device to arrest the vibrator at the completion of the throw required to position the active color band over the printing point. 110 115 120

11. In a front-strike writing machine, the combination with a platen shiftable to up- 125 130

per and lower case positions, of a ribbon vibrator, a bichrome ribbon carried thereby, a universal bar, an actuator for said vibrator, a switch connecting the universal bar and actuator for operating the latter to throw the ribbon vibrator upwardly and position the ribbon over the printing point, said switch shiftable to vary the connections between the universal bar and actuator, and thereby vary the throw of the vibrator to bring different color bands of the ribbon into activity, and a stop device to limit the throw of the vibrator, said stop device shiftable by said shifting of the switch and having different stop surfaces thereby brought into position to arrest the vibrator at the completion of the throw required to position the active color band over the printing point.

12. In ribbon vibrating mechanism for a typewriting machine, the combination with a ribbon vibrator, of an actuator therefor, a universal bar, and a device forming a connection between the universal bar and said actuator, said device pivotally mounted on the universal bar and comprising wings, said device movable about its pivot to bring the wings alternatively into operative relation to the actuator, said wings being divergent, and each brought into a position parallel with the plane of movement of the actuator when in operative relation to the actuator, and means to hold said device in an intermediate position in which it is disconnected from the actuator to silence the ribbon vibrator. 130

13. In ribbon mechanism for a typewriting machine, the combination with a ribbon vibrator, of an actuating lever therefor, a universal bar, a switch pivotally mounted on the universal bar and forming a connection between said bar and actuating lever, said switch comprising divergent slotted wings on opposite sides of the actuating lever, pins on said lever at different distances from its fulcrum to respectively engage the slotted wings, said switch movable about its pivot to move said wings into engagement with said pins, each of said wings when in engagement with a pin lying in a plane parallel with the plane of the actuating lever, and means to hold the switch in an intermediate position in which it is disconnected from both pins to silence the ribbon vibrator. 140 145 150

14. In a typewriting machine, the combination with a platen, of means to shift the platen up and down comprising a shift rail, a type-bar segment in front of said rail, a ribbon vibrator, an actuator therefor, a support on which said actuator is mounted, said support mounted to slide up and down on said segment, and a connection between the shift rail and said support to move the latter up and down with the shift rail. 155 160

15. In a typewriting machine, the combination with a ribbon vibrator and a platen shift rail located behind the vibrator, of a supporting plate in front of the shift rail and at one side of the vibrator, a lever mounted on said plate and connected to the vibrator to operate the latter, a universal bar, operating connections between the universal bar and said lever for actuating the

lever and thereby operating the vibrator, 10 and means connecting said supporting plate and shift rail to shift said plate up and down with the shift rail.
